UNITED STATES PATENT OFFICE.

PHINEAS W. VAUGHAN, OF DE KALB, ILLINOIS.

IMPROVEMENT IN GRINDERS FOR HARVESTER-KNIVES.

Specification forming part of Letters Patent No. 122,083, dated December 19, 1871.

To all whom it may concern:

Be it known that I, PHINEAS W. VAUGHAN, of De Kalb, in the county of De Kalb and State of Illinois, have invented an Improved Sickle-Grinder, of which the following is a specification:

The present invention relates to an improvement in that class of grinders which is used to sharpen the knives of sickle-bars; and its nature consists in the use of a horizontal stone which is inclosed at its periphery with a rectangular frame having adjustable end pieces, which are provided with notches to form a suitable rest for holding the knives properly on the stone during the process of grinding them, as the whole is hereinafter fully described and shown.

In the drawing, Figure 1 is a perspective representation of my improved sickle-grinder; Fig. 2, a vertical sectional elevation of the same; Fig. 3, an elevation of one of the adjustable end pieces detached from the other part of the rectangular frame.

A represents a substantial bed, which is mounted on legs B and supports the mechanism of the grinder, hereinafter described. E represents the stone, which is hung to a vertical shaft, shown by dotted lines S, the lower end of the shaft resting in a step fixed to the cross-piece v. This shaft S has fastened to it below the stone E a gear-wheel, R, which meshes into a drive-wheel, P, so that when the crank D is turned the shaft W of the wheel P is rotated; consequently the stone E is put in motion. H H' represent the side pieces of a rectangular frame, which are made of wood or other suitable material, and which are provided with slots N N at their ends to receive the tenons a a of the end pieces H'', and the ends of screw-rods J. The object of putting the ten-

ons a in the slots N is that the ends H'' may be adjusted to or from the stone E, so that sickles of different patterns may be ground, and the object of the screw-rod is to clamp the frame together. The side piece H' is fastened to the end of the bed A and the side to the top of bed; but they may be fastened in any other manner most convenient. I I I I I represent notches formed in the top parts of the side H' and ends H'', for the purpose of forming rests for the knives of the sickle-bar to bear against when being sharpened.

To use the device the knives, as attached to the sickle-bar, one at a time, are to be placed against the outside of the notched parts I I, while the inner and first edge of the next knife is brought upon the stone, so as to form the proper bevel. This adjustment is readily made by following the bevel previously formed on the knife. To grind the opposite edge of the tooth, turn the sickle-bar over and bring the knife against the opposite side of the notch. The position of the sickle-bar is shown at Fig. 1.

Having thus described my invention, what I claim, and desire to secure by Letters Patent, is—

1. The rectangular frame H H' H'' H'', made adjustable by means of slots N, tenons a, and rods J, and provided with notches I I, as and for the purpose set forth.

2. The combination of the adjustable frame H H' H'' H'', bed A, stone E, and gearing R W, substantially as described and shown.

PHINEAS W. VAUGHAN.
